UNITED STATES PATENT OFFICE

2,194,311

SWITCH OPERATING MECHANISM

Vincent W. Leonard, Saugus, Mass., assignor to
General Electric Company, a corporation of
New York

Original application August 8, 1935, Serial No.
35,316. Divided and this application June 7,
1938, Serial No. 212,274.

12 Claims. (Cl. 200—27)

My invention relates to switch operating mechanism and more particularly to intermittent switch operating mechanisms used as timing mechanisms for traffic controllers. This application is a division of my application Serial No. 35,316, filed August 8, 1935.

One object of my invention is to provide an improved adjustable mechanism to facilitate the adjustment of the periods between switch operations.

Another object of my invention is to provide an improved adjusting mechanism to facilitate the adjustment of time periods between switch operations for a cycle of operations and simultaneously to provide a phase adjustment of an operating cycle relatively to other cycles in the same time switch or in similar switches in an interconnected system.

For a better understanding of my invention, together with other and further objects thereof, reference is had to the following description taken in connection with the accompanying drawing, and its scope will be pointed out in the appended claims.

In the accompanying drawing, Fig. 1 illustrates a front view, partly in section, of my improved mechanism; Fig. 2 is a side view in section of the same device; Fig. 3 is a front view of a traffic signal controller equipped with the mechanism illustrated in Figs. 1 and 2; and Fig. 4 is a side view of a switch actuating key.

Referring to the drawing in detail, Figs. 1 and 2 disclose a switch operating mechanism including a dial composed of a face plate 10, a back plate 11 in the form of a ring, and intermediate spacing rings 12 and 13. These members are spaced from each other by washers 14 placed respectively between each pair of adjacent members, and are held in assembled relation by rivets 15 equally spaced about the center of the face plate. The face plate is provided with a group of radial slots 17 arranged near the periphery of the plate. These slots are equally spaced about the center of the plate, and in the illustrated example, one hundred slots are provided and markings placed at each tenth slot. The face plate is further provided with a slot 18 and a sight opening 19 which is in the shape of two intersecting circles, the points of intersection forming indicator points for the sighting of the position of the face plate relatively to a core member 20.

The back plate 11 of the dial is provided with radial slots 21 corresponding to the slots 17 in the face plate. The intermediate spacing rings

12 and 13 are of a smaller diameter than the face plate and the back plate, thereby forming a groove, in the assembly, into which a helical spring 22, in the form of a closed ring, is sprung. The spacing rings 12 and 13 are provided with open ended slots 23 which are aligned with the slots 17 and 21 of the face plate and back plates, respectively, but do not extend to the outer ends of the slots 17 and 21 in the face plate and back plates, respectively.

The face plate 10 is rotatably mounted on a hollow shaft 25 and contiguous to the core member 20. This core member is rigidly attached to the hollow shaft 25, is provided with markings corresponding to the markings of the slots 17 in the periphery of the face plate and may therefore be termed a secondary dial. The face plate, which may for convenience be called the primary dial in order to distinguish it from the secondary dial, is held in contiguous relationship to the secondary dial 20 by a helical spring 26 which surrounds the reduced end 27 of the hollow shaft 25 and is held under compression by a collar 28 attached to the reduced end 27 by a set screw 29. This frictional engagement of the secondary dial with the face plate is effected so that the face plate may be moved angularly relatively to the secondary dial, whenever it is desired to change the relationship between the peripheral slots, on the face plate, and the secondary dial. It is further desired to lock the face plate, in the desired position, to the secondary dial 20 to prevent relative movement during operation. For this reason, the secondary dial 20 is provided with peripheral serrations 30 which are aligned respectively with the graduation markings on the dial. The face plate is provided with a knife edged lever 31 which projects through the slot 18 in the face plate and is pivoted upon a bracket 32 attached to the back of the dial assembly. The lever moves about a pivot pin 33 and is urged in a clockwise direction about this pivot pin by a spring 34. The spring urges this lever into contact with the secondary dial 20 and effects an engagement between the lever, which is at this point provided with a knife edge 35, and the serrations on the periphery of the secondary dial. When it is desired to change the relationship between the dial assembly and the core, it is only necessary to move the lever 31 upwardly in its slot 18 to lift the knife edge 35 out of a serration 30 and turn the dial assembly until the desired relationship is obtained. The graduation markings on the secondary dial are easily visible.

through the opening 18, and the indicator point is lined up with the knife edge of the lever 31 and that radial slot 17 on the face plate which is marked "0".

5 For the purpose of rotating the dial assembly, the hollow shaft 25 is provided with a gear 36 rigidly attached to it, and the hollow shaft is mounted for rotation upon a solid shaft 37. This solid shaft in the illustrated example is attached 10 to a panel 38 by having its reduced end 39 projected through an opening in the panel until a collar 40 on the shaft is in contact with the face of this panel. The end of the reduced portion 39 is then riveted over to hold rigidly this 15 shaft perpendicularly to the face of the panel. The collar 40 is then a spacer for maintaining a spaced relationship between the gear 36 and the panel 38. To prevent the dial assembly from slipping off the end of the shaft, a washer 41 is 20 attached to the other end of the shaft and held in place by a screw 42. The entire assembly is driven at a predetermined speed by a gear 43 on the end of the motor driven shaft 44 projecting through the panel 38. The exact relationship of 25 the two gears 36 and 43 and their respective shafts 37 and 44 is better illustrated in Fig. 3. The gears are of the same size and the driving gear is used to drive several dial assemblies. Fig. 1, therefore, illustrates the driven shaft 30 forward of and below the shaft 37. The shaft 44 is preferably operated by a synchronous motor. The speed of such motors is dependent upon the frequency of the alternating current supplied to it, and since it is possible to maintain 35 constant frequency on a distribution system, the speed of such motors is predetermined and constant.

In Figs. 2 and 3, I have illustrated switch mechanisms operable by the dial assembly above described. This switch mechanism comprises a pair of contact springs 46 and 47 rigidly held on the face of the panel 38 by blocks 48 and 49. The free ends of these contact arms project into slots 50 and 51 in a block 52. The 45 slots are so arranged that the spring arms are held in a position such that contacts 53 and 54 carried by the spring arms respectively are held in an open circuit position. The lower contact arm 46 is provided with a finger 55 attached to the arm by an insulating block 56, so that when during the operation of the dial mechanism, a key engages this operating finger, the lower contact 53 is raised into engagement with contact 54 to make a circuit through 50 an operating coil 57 indicated in dotted lines.

The dial mechanism above described operates the switch 46-47 by means of keys inserted in some of the radial slots. Figs. 2 and 4 illustrate side views of the operating keys which are 55 inserted in the slots 17 for the purpose of actuating the switch mechanisms mounted on the panel 38. The key 60 at the top of Fig. 2 is placed in the slot marked "0", and is, therefore, the reference key. It is not intended to be 60 moved, and is, therefore, provided with only a small head 61. It is a sheet metal key of sufficient length to project under the pair of contact arms 46 and 47. It is provided with indentations 62 on its edges. When the key is 65 moved through the slot 17 in the face plate, it raises slightly the spring 22 which, when the key is in its proper positions, falls into the outer one of the indentations 62 and holds the key in position. This key 60 is a reference point 70 for the positioning of a key 63 (see Figs. 1 and 4)

corresponding to the key 60. Key 63 is provided with a larger head 64 so that it may be easily removed and replaced. Only one of these keys 63 is illustrated in Fig. 1, but any desired number may be used. The number of these keys 5 that is placed in the slots 17 is dependent upon the number of actuations that is desired during one revolution of the dial assembly, and they are spaced in accordance with the relative lengths of the intervals, between switch actuations, that 10 are desired. A third key 65 is provided to operate a second pair of contacts 66 and 67, which are similar to and placed parallel to the contacts 53 and 54, but closer to the panel. The key 65 is longer than the keys 60 and 63, and operates both pairs of contacts simultaneously. This key is provided with a rectangular head 68 which is large enough to enable an operator 15 to change easily its position and to distinguish it from the keys 63. The key 65 functions to 20 operate in the same manner as the keys 60 and 63 to operate the first pair of contacts and operates the second pair of contacts once during each revolution of the dial. The instant of 25 this actuation is easily determined since the key 25 is distinguished from the other keys by its rectangular head. Each of the three keys 60, 63, and 65, therefore, operates the contacts 53-54 but only key 65 operates the second pair of contacts 66-67. 30

In Fig. 3 I have shown the front view of the panel 38 on which three of the above-described dial assemblies are provided, each being driven by the gear 43. Each of these dials may be adjusted relatively to the others merely by lifting 35 the lever 31 and turning the face plate relatively to the secondary dial 20, and in each plate, the keys will be spaced in accordance with the desired timing of switch operations. A cover 70 is provided to cover the contacts and the dials. Openings 70' are provided to register with each dial mechanism so that it may be visible when the cover is in closed position. Another opening 71 is provided in the cover to register with a dial 72. This dial 72 carries indicia which may be 40 used to indicate the time period for which the dial rotations are adjusted. In this figure, the cover 70 is broken away to illustrate fully the switch contacts operated by one of the dials, and illustrates partly contacts operated by another dial. Each dial operates a similar set 45 of contacts. The contacts may be arranged to close a circuit intermittently to any desired apparatus wherein the actuations must be accurately timed. Fig. 3 merely illustrates one application 50 of the dials. In this illustration, the panel 38 is that of a traffic signal controller in which each dial is arranged to control traffic signals through a definite time sequence. The secondary dials are driven in a predetermined 55 fixed relationship relatively to each other from the main drive shaft 44 through the interconnecting gears 43 and 36. The markings on the primary dials and on the secondary dials correspond to each other and also correspond to other 60 pairs of dials in the same controller. The relative adjustment of the several primary dials relatively to their secondary dials therefore indicates 65 the relationship between operating cycles controlled by the several dial mechanisms. Several 70 of such controllers may be used in a traffic control system, and since the drive shafts of the several controllers may be maintained in synchronization as described, for example, in application Serial No. 35,316, of which the present ap- 75

5 plication is a division, the relationship indicated between the primary and secondary dials of one controller also indicates the relationship between the various operating cycles in the system. Only one of the dials is effective at any one time and switching means are provided so that each dial may be selected to effect operation of the signals.

10 The herein described mechanism is simple both in construction and operation. The dial is assembled of sheet metal members into which the key slots are readily stamped, and its mounting upon the shaft of the core member is readily accomplished by a simple friction device comprising the spring and collar. In operation the keys 15 may be readily inserted in any desired one of the peripheral slots, and are tightly held therein by the spring in the groove. When these keys are placed in the slots in order to obtain the desired cycle of operation, this dial may be turned 20 relative to its secondary dial to adjust it in relation to any other dial in the system.

What I claim as new and desire to secure by Letters Patent of the United States is:

1. In a switch actuating mechanism, the combination of a rotatable dial including a core member, a face plate angularly adjustable relatively to said core member and provided with radial slots, keys for operating switch members projecting through said slots, means in said dial 30 for holding said keys in said slots, and means for locking said dial in any desired angular relation to said core member.

2. In a switch actuating mechanism, the combination of a rotatable dial including a face plate 35 provided with radial slots, a groove in the periphery of said dial, keys for operating switch members projected through said slots and through said groove and a helical spring in said peripheral groove, the helices of said spring which register with said slots, respectively, being lifted by each key as it is moved into position in said slot and being respectively held in engagement with said keys to hold the latter in their respective 40 positions in the dial.

45 3. In a switch actuating dial, the combination of a face plate, radial slots in said face plate arranged near the periphery thereof, keys arranged in said slots at predetermined intervals and projecting through said face plate, means for holding said keys in said slots, a core member for said face plate, a shaft rigidly attached to said core member for rotating same, means for holding said face plate and said core member in frictional engagement so that these members may be readily 50 rotated relatively to each other, and locking means for locking said face plate and said core member in any desired angular relation relatively to each other.

55 4. In a traffic signal controller, the combination of a rotatable shaft, a core member comprising a disk attached to said shaft, a second disk mounted upon said shaft and rotatable relatively to said core member and provided with peripheral slots, a ring provided with slots corresponding to the slots in said disk member attached to and spaced from said disk member, keys projecting through corresponding pairs of slots in said ring and disk, a switch member in the path of said rotatable keys, and means for locking said disk member in any one of a plurality of positions relatively to said core member.

60 5. In a traffic controller, the combination of a rotatable shaft, a core member comprising a disk mounted upon said shaft and rotatable there- 75 with, a disk member mounted on said shaft and

rotatable relatively thereto and provided with peripheral slots, a ring attached to and spaced from said disk provided with slots corresponding to the slots in said disk, keys projecting through corresponding slots in said disk and said ring, means for locking said keys in said slots comprising a helical spring mounted between said ring and said disk and engaging the outer edge of said keys, means for locking said disk in any one of a plurality of positions relatively to said core member, and a switch mounted in the path of movement of said keys and intermittently operable thereby.

6. In a switch operating mechanism the combination of a rotatable shaft, a core member 15 comprising a disk mounted upon said shaft and rotatable therewith, a disk member mounted on said shaft and rotatable relatively thereto and provided with peripheral slots, a ring attached to and spaced from said disk provided with slots 20 corresponding to the slots in said disk, intermediate spacing rings between said disk and said first-mentioned ring, said intermediate rings having a diameter smaller than said disk in said first ring and being provided with open-ended 25 slots corresponding to the lower portion of the slots in the disk in said first mentioned ring, keys projecting through corresponding slots in said disk and said intermediate rings, and a helical spring mounted between said ring and said first-mentioned ring, said spring resting on the peripheries of said intermediate rings and upon the outer edge of each of said keys to lock the same in position, means for locking said disk in any one of a plurality of positions relatively to 30 said core member, and switch members mounted in the path of movement of said keys and intermittently operable thereby.

7. In a switch actuating mechanism, the combination of a primary dial, radial slots in said primary dial arranged near the periphery thereof, keys arranged in said slots at predetermined intervals and projecting through said primary dial, means for holding said keys in said slots, a secondary dial associated with said primary dial, a 45 shaft rigidly attached to said secondary dial for rotating it, means for holding said primary dial and said secondary dial in frictional engagement and in rotatable relation to each other, and locking means for locking said primary dial in any 50 desired angular relationship to said secondary dial.

8. In a traffic signal controller, the combination of a rotatable shaft, a secondary dial comprising a disk attached to said shaft, a primary 55 dial mounted upon said shaft and rotatable relatively to said shaft and secondary dial and provided with peripheral slots, a ring provided with slots corresponding to the slots in said primary dial attached to and spaced from said primary dial, keys projecting through corresponding pairs of slots in said ring and in said primary dial, a switch member in the path of said rotatable keys, and means for locking said primary dial in any 60 one of a plurality of positions relatively to said secondary dial.

9. In a traffic signal controller, the combination of a plurality of primary dials, a secondary dial associated with each primary dial, means for adjusting each primary dial relatively to its secondary dial independently of the adjustment on the other primary dials, and means for driving said secondary dials in a predetermined fixed relationship relatively to each other.

10. In a traffic signal controller, the combina- 75

tion of a plurality of primary dials, a secondary dial associated with each primary dial, means for adjusting each primary dial relatively to its secondary dial independently of each other primary dial, a drive shaft for each secondary dial, a common drive shaft operated by said controller and a gear drive between said common drive shaft and said secondary dial shafts for driving said secondary dials in a predetermined fixed relationship relatively to each other.

11. In a traffic signal controller, the combination of a drive shaft, a plurality of secondary dials, means for driving said secondary dials in a predetermined fixed relation relatively to each other and relatively to said drive shaft and a primary dial associated with each secondary dial each of said primary dials being adjustable relatively to its associated secondary dial independ-

ently of the relative adjustment between the other of said primary and secondary dials on the controller.

12. In a traffic signal controller, the combination of a drive shaft, a plurality of secondary dials, shafts for driving said secondary dials respectively, gears attached to said secondary dial shafts and to said main drive shaft respectively and in engaged relation with each other for driving said secondary dials in a predetermined fixed relationship relatively to each other and relatively to said drive shaft, primary dials associated with said secondary dials respectively and adjustable relatively thereto, and locking means for maintaining any desired relationship between each primary and secondary dial.

VINCENT W. LEONARD.
